METHOD OF DRILLING WELLS

Filed Oct. 6, 1931

UNITED STATES PATENT OFFICE

LELAND PAUL KINNEAR, OF BEAUMONT, TEXAS

METHOD OF DRILLING WELLS

Application filed October 6, 1931. Serial No. 567,280.

The invention relates to new and useful improvements in a method of drilling deep wells, such as oil or artesian wells.

An object of the invention is to provide a method of drilling wells whereby a pipe section may be utilized for operating the drill bits for drilling the well, and said pipe section converted into a casing for the well without removing the same from the well.

10 A further object of the invention is to provide a method of drilling wells of the above character wherein the drilling of the well is continued through the converted pipe casing.

15 A still further object of the invention is to provide a method of drilling wells wherein pipe sections having detachable bits are utilized for drilling a portion of the well, after which the bits are removed and the pipe 20 section converted into a casing for the well and the well sealed, after which the drilling of the well is continued by the smaller pipe section having detachable bits which are passed through the converted pipe casing.

25 These and other objects will in part be obvious and will in part be hereinafter more fully disclosed.

In the drawing which shows by way of illustration one embodiment of the invention—

30 Figure 1 is a sectional view through a series of pipe sections and a detachable bit mechanism associated therewith showing one form of structure which may be used in carrying out the improved method;

35 Fig. 2 is a view similar to Figure 1, showing the bit mechanism removed from the pipe sections without withdrawing the pipe sections from the well;

40 Fig. 3 is a view similar to Figure 2, showing the lower end of the lowermost section with the cement seated in place for sealing the well;

45 Fig. 4 is a view similar to Figure 3, showing the chuck for the tools and the plug formed during the sealing of the well cut away so that the drilling of the well may be continued through said pipe sections as the casing for the well, and

50 Fig. 5 is a diagrammatic view illustrating

one way of drilling a well by my improved method.

The invention is directed to a method of drilling wells and more particularly to deep wells, such as oil wells or artesian wells, although the invention may be used for drilling a dry test well, or any type of well. In carrying out the invention, a pipe section is used to which drill bits are detachably connected. This pipe section is used as an actuating means for operating the drill bits. Preferably the drill bits are of a character which are rotated, and the pipe section is connected to a suitable device whereby it is rotated and fed forward during the drilling of the well. After the well has been drilled to a desired depth, or condition of earth formation where it is desired to seal the well, or, if for any reason, it is not desirable to proceed further with the drilling of the well with the pipe sections being operated, then the drill bits are removed and the well is sealed. The well may be sealed either by the use of cement, or by a formation seal caused by a movement of the pipe and the embedding of the lower end thereof in the earth. After the seal has been produced, it may be necessary to cut away the lower pipe section in the region where the drill bits are attached, and this may be accomplished by any suitable metal cutting means operated through the pipe section. Thus the pipe section or sections used for drilling are converted into a well pipe casing. A smaller pipe section having detachable bits is then inserted through the converted well pipe casing and the drilling of the well proceeds. The smaller pipe sections are used for operating the drills, and again, if a condition of earth formation occurs making it desirable, the pipe sections used for operating the drills may, in a similar manner, be converted into a well pipe casing, a seal for the well produced, said lower pipe section and seal cut away, if found necessary, and the further drilling of the well continued by the use of a still smaller pipe section.

The invention will possibly be better understood by a more detail description of

one form of apparatus which may be used for carrying out the invention, and by a description of the manner of utilizing the invention for drilling a well.

5 In Figure 1 of the drawing, a series of pipe sections is shown with a chuck attached to the lower end thereof through which the drill bits are detachably connected to the pipe sections. The pipe section 1 is connected to the chuck 2. A pipe section 3 is connected to the upper end of the pipe section 1. A pipe section 4 is connected to the upper end of the pipe section 3, and so on, pipe sections are attached as the drilling 10 of the well proceeds. These pipe sections, as shown in the drawing, are so constructed that when they are joined, the inner diameter of the pipe sections is substantially uniform throughout. To this end, each pipe 15 section is provided with an integral collar 5 at the upper end thereof which has a threaded recess to receive the threaded end of the next above pipe section. The joint 20 may be made in any suitable way, but it is 25 desirable that the pipe shall be of uniform diameter within so as not to interfere with the insertion and removal of the drill bits, and also so as not to interfere with the use 30 of the pipe sections as a well pipe casing, as will be referred to later.

The chuck 2 attached to the lower end of the pipe section 1 is provided with a recess 6 of slightly smaller dimensions than the bore of the pipe section attached to the 35 chuck. There is an opening 7 leading from this recess to the lower end of the chuck, thus forming shoulders 8, 8. The drill bits are indicated at 9, 9, in Figure 1 of the drawing. These drill bits are independent 40 of each other, and each is provided with a shank 10. A cable 11 is attached to each shank, and this cable is in turn attached to a rod 12. The rods 12 are attached to a collar 13 mounted for free movement longitudinally of a pipe 14. The pipe 14 at its lower end is attached to a collar 15. A spring 16 bears against the upper end of the collar 15 and against the lower end of the collar 13. The drill bits are collapsed, 45 and pass through the opening 7 after which they are moved laterally into drilling position on the chuck. The drilling bits are forced into seated position by wedge bars, one of which is indicated at 17. The drill 50 bits are forced from seated position to a position where they may be detached from the chuck, by wedge bars, one of which is indicated at 18. The wedge bars 18 are attached to a collar 19 mounted on a sleeve 20 which is free to move on the pipe 14. The wedge bars 17 are attached to the collar 15. The upper ends of the shanks 10 are tapered so as to properly cooperate with the inner 25 tapered ends of these wedge bars. When it 60 is desired to disconnect the drill bits from

the chuck, the releasing means is lowered through the pipe sections and connected to the collar 21 at the upper end of the pipe section 14. This pipe section is threaded into the collar 15 and the first movement 70 of the pipe section 14 in an upward direction will withdraw the wedge bars 17, thus releasing the bits so that the wedge bars 18 connected to the collar 19 will move downward through the weight of the parts and thus unseat or disconnect the bits from the chuck. The upward movement of the pipe 14 before the bits are disconnected, compresses spring 16, and as soon as the bits are 75 detached from the chuck, the spring will lift the collar 13 to its normal position on the pipe 14. When it is desired to attach the bits to the chuck, they are lowered through the pipe sections and through the 80 chuck to seated position, and when the shoulders on the shank engage the shoulders 8 on the chuck, then the further downward movement of the bit ceases. The collar 19 carrying the wedge bars 18 will, however, 85 continue their downward movement and force the bits laterally to seated position on the chuck. This construction of chuck and detachable bit mechanism per se, forms no part of the present invention, but is 90 shown, described and claimed in my co-pending application Serial No. 567,941, filed 95 of even date herewith. The detail description has been given for the purpose of illustrating one form of detachable bit which may be used in the carrying out of my improved method of drilling wells.

In Fig. 2 of the drawing, the drill bits and the mechanism associated therewith are shown as detached from the chuck and pipe sections. In Fig. 3 of the drawing, one form of seal is shown which is made after the drill bits have been removed from the pipe sections. In this form of the invention, cement is poured through the pipe sections forming a seal 22 for sealing the 100 well. When a chuck of the type disclosed is used, and it is desired to continue the drilling of the well by my improved method, suitable metal cutting means is lowered 105 through the pipe sections and the chuck is cut away at the lower end thereof and also the plug formed by the cement seal, so as to provide an opening 23 which is of substantially uniform diameter throughout the 110 chuck. This may be done by metal cutting 115 tools or any other desired mechanism. The essential feature is to provide an opening through the chuck and the seal, if one is not already present, so that the pipes used for operating the bits may be converted into a 120 well casing, and the drilling of the well continued through this pipe casing. If the chuck is constructed so that the bits when 125 detached therefrom have substantially a uniform opening therethrough, then of course, 130

it will not be necessary to cut away the metal of the chuck. Furthermore, instead of a cement seal, a formation seal may be produced by the moving of the pipe endwise 5 and the embedding of the lower end thereof in the earthy material. In this case, it will not be necessary to cut away the seal, but the drilling will continue by the use of smaller pipe sections carrying detachable 10 bits which are passed through the pipe sections 1, 2, 3, 4, etc.

With this description of one form of apparatus for carrying out the invention, the drilling of a well by my improved method 15 will now be described. This method of drilling is illustrated diagrammatically in Fig. 4. The well is first drilled of relatively large diameter and as deep as necessary to case off sluffing surface sand, or formations 20 of earth, and protect the derrick foundation. As shown in Fig. 5, this first drilling operation is extended to a depth of forty feet, and a casing 24 with a seal 25 is utilized. The first drilling may be accomplished by my 25 improved detachable bit and pipe section which is converted into a casing in the manner described above. It may, however, be formed in the ordinary manner of drilling, and the inserting of a casing after the de- 30 sired depth has been reached. The seal 25 may be formed of cement inserted through or around the pipe casing 24, or it may be of a formation character produced by the moving of the casing endwise until it be- 35 comes firmly embedded in the earth structure. After this first formation of the well, then a smaller pipe section 23 is used to which detachable bits are connected. This pipe section 23 is made up, of course, of sec- 40 tions which are joined, and they are of the character described above, and as shown in Fig. 1. The drilling continues under normal conditions until a depth of three thousand, five hundred feet is reached, at which 45 point it is found necessary to seal the well. A seal 26 is then formed at the lower end of the lowermost pipe section or chuck after the drill bits have been detached. The chuck and seal are then cut away and a smaller 50 pipe section 27 is utilized with detachable bit sections for the continuing of the drilling of the well. This pipe section 27 is also made up of sections joined together in the manner described in connection with Fig- 55 ures 1 and 2. When the desired depth is reached, a seal 28 may be formed after the bits have been removed, and this seal may be a cement seal or a formation seal, the same as the seal 25 and the seal 26. After 60 removing the drill bits and sealing the well, the pipe sections used for operating the drill bits are again converted into well pipe casings, and this is accomplished without withdraw- 65 ing the pipe sections from the well. The same is true of the pipe section 23. The

bits are detached and removed and the chuck and seal cut through, if necessary, in order to convert the pipe sections used for operating the drill bits into a well casing. A 70 perforated casing 29 may be inserted if the oil sand has been reached.

It is understood, of course, that my method may be otherwise employed in the drilling of wells than that described in detail and diagrammatically shown in Fig. 5. If, for example, in drilling a well, a crooked hole 75 is formed which causes the pipe sections operating the drill bits to bind and stick fast, the drill bits can be detached, the chuck cut away, if necessary, thus converting the 80 pipe sections used for operating the bits into the well casing, and the drilling of the well continued by the use of smaller pipe sections carrying smaller detachable drilling bits. 85

It sometimes occurs in drilling a well that at a depth of three thousand feet or thereabouts, quicksand, heaving shale, or a sluffing avalanche formation is reached which is liable to fall in and interfere with the 90 operation of the drilling pipe. By the present method, this earth formation may be passed by reason of the fact that the bit can be changed in a very few minutes, and the pipe kept moving upwardly and 95 downwardly and rotating while the bits are being changed. Furthermore, the circulation of fluid through the aid of powerful mud pumps may be utilized to keep back 100 the sluffing formation which interferes with the manipulation of the drill pipes. If I am unable to pass through this bad forma- 105 tion just referred to, then the pipes for operating the drill bits may be converted into a well pipe casing and the drilling 110 of the well continued by the use of a smaller pipe in the manner above described.

While the invention is described as useful in the drilling of oil wells and artesian wells, it will also be useful in the drilling of dry 110 test wells, and for any purpose where it is desired to drill a deep well through various earth formations. It will be apparent that by my improved method of drilling wells, 115 not only is there a great saving in the operation of drilling, but there is also a great saving in the piping used for the drilling operation and the casing of the well.

Having thus described the invention, what I claim as new and desire to secure by Letters Patent, is—

The method of drilling wells consisting in detachably connecting drill bits to a chuck attached to the lower end of pipe sections, which chuck has formed integral 125 therewith portions spaced a less distance than the diameter of the pipe sections above the chuck and contacting with said bits for rotating the same, detaching the drill bits from the pipe sections, cutting away the 130

interior portion of the chuck to substantially the same diameter as the pipe section thereabove for converting said chuck and the pipe section thereabove into a casing for the well and without removing the chuck from the well, and passing a pipe section of smaller dimensions through the first-

named pipe section having drilling bits connected thereto and utilizing the last-named pipe section for rotating and feeding the drill bits for continued drilling of the well.
